UNITED STATES PATENT OFFICE.

SALVATORE SCOGNAMILLO, OF NEW YORK, N. Y.

DESIGN FOR AN AUTOMOBILE-HORN.

44,452.

Specification for Design.

Patented Aug. 5, 1913.

Application filed October 30, 1911. Serial No. 657,619. Term of patent 7 years.

To all whom it may concern:

Be it known that I, SALVATORE SCOGNAMILLO, a citizen of the United States, residing at New York, in the county of New York and State of New York, have invented a new, original, and ornamental Design for Automobile-Horns, of which the following is a specification, reference being had to the accompanying drawing, in which—

The figure is a side elevation of an automobile horn showing my new design.

I claim:

The ornamental design for an automobile horn, as shown.

SALVATORE SCOGNAMILLO.

Witnesses:

CHAS. S. HYER,

F. B. KEEFER.
